UNITED STATES PATENT OFFICE.

SALVATORE ANDRIOLA, OF NEW YORK, N. Y.

HAT PROTECTOR.

Application filed January 12, 1927. Serial No. 160,749.

This invention relates to hat protectors in general and particularly to the kind adapted to prevent a hat, made of material affected by dampness, from becoming wet.

5 One of the objects of my invention is to provide a hat protector of such construction that it will by itself collapse into a minimum space when not in use.

Another object of my invention is to provide 10 a hat protector which will, when placed upon the hat, firmly grip the corner of the hat formed between the crown and the brim and also prevent simultaneously, an excessive stretching of the material of the hat 15 protector covering the top of the crown and covering the brim of the hat.

Another object of my invention is to provide 20 in such hat protector, means for firmly engaging the outer edge of the brim of a hat without the necessity of folding the material of the hat protector over that edge.

The foregoing and further objects will be more fully apparent from the following description and the accompanying drawings 25 forming part of this disclosure in which,

Figure 1 represents a cross sectional view taken on line 1—1 of Figure 2, showing my device in a semi-collapsed form,

Figure 2 is a bottom view of my device 30 and,

Figure 3 is a cross sectional view of my device illustrating its adaption to a hat.

Before describing my invention in detail, I believe it essential to make a general comparison 35 of similar devices heretofore used and my device, which will enable me to show the difference and advantages over the existing art.

Hat protectors are well known. Mostly 40 they have been so constructed that the material, usually of elastic nature, is brought over the brim of the hat, and held together by either the elasticity of the material itself, or by means of elastic bands or strings by 45 means of which, the material may be drawn together. In each of these constructions the danger of breaking the material at the edge of the brim is quite obvious.

Referring to the drawings, numeral 10 50 denotes the upper portion of my hat protector adapted to cover the top of the crown. Member 10 possesses at its outer periphery, a reinforcing band 11, to which is connected an intermediate member 12, consisting of a 55 ring-like portion, the inner edge of which, terminating in a reinforcement 13. The lat-

ter is of somewhat heavier construction than reinforcement 11 as is plainly evident from the drawings. This reinforcement 13 is the one member which is subjected to a stretching operation when the protector is being placed upon the head. 60

Between the reinforcement 13 and a still larger reinforcement 14, is a ring-shaped member 15. 65

The construction of member 12 and its connection between members 10 and 15 causes my device to automatically collapse into a flat position when the protector is not in use. 70

Referring to Figure 3, it will be seen, that when the hat protector is mounted upon the hat, reinforcement 13 is stretched considerably, while reinforcement 14, engaging the brim 16 of the hat, indicated in broken lines, 75 is also stretched, together with member 15. The top member 10, however, remains unstretched and only the lower part of member 12 is partially expanded, until it changes its original ring shape to cylindrical form. 80 In this manner, the material of the hat protector is prevented from becoming defective due to an over strain put upon these parts of the device and that the bands 13 and 14, particularly band 13, are subjected 85 to stretching.

Due to their sturdy construction, these parts are made safe against breakage.

My device is particularly intended for covering straw hats made of stiff material. It 90 is well known that the outer edge of the brim of a straw hat is usually provided with a plurality of prongs or similar design which will imbed themselves into the reinforcing member 14, thereby holding the latter in the 95 desired position and prevent it from becoming disengaged from the hat.

I prefer constructing my device from elastic material and employ preferably round rubber bands for reinforcements 11, 13 and 100 14. However, the material from which members 10, 12 and 15 are made, do not necessarily have to be made of rubber and an impregnated silk or cotton material will 105 answer the purpose, in which case, the portions of members 12 and 15 nearest to reinforcement 13, will take on a form of pleats which will allow for the stretching of these members. This construction is not shown in the drawings since it is self-evident. 110

While I have mentioned that my device is intended particularly for the use in connec-

tion with straw hats, be it understood that any other hat may be provided with my device and its construction changed accordingly provided however, that the principle of collapsibility and the principle of attachment are adhered to.

Having thus described my invention and reserving for myself the right to make such changes and improvements as may be necessitated by the application of my invention to variously shaped hats, I claim:

- 15 1. A hat protector, comprising a body composed of a plurality of distinct sections united at their edges, and consisting of a flat top section and substantially ring-shaped bottom and intermediate sections, normally in adjacent relation to each other, resilient reinforcements provided at their joints and an additional reinforcement arranged at the outer edge of the largest of these sections, adapted to be engaged by the edge of the brim of a hat.
- 20 2. A hat protector, comprising a body composed of three distinct sections, connected with each other, and consisting of a flat top section and substantially ring-shaped bottom and intermediate sections, normally in adjacent relation to each other, resilient reinforcements provided at their connections and a resilient reinforcing member associated with one of said sections adapted to be engaged by the outer edge of the brim of a hat, said intermediate section adapted

to assume a cylindrical shape when the protector is mounted upon a hat.

3. A hat protector, comprising a body of waterproof material composed of three distinct sections adapted to normally collapse, when not in use, into flat position and so that one section rests upon the other, said sections consisting of a flat top section and substantially ring-shaped bottom and intermediate sections, and provided at their joints with resilient reinforcements, and another reinforcement provided at the outer edge of the largest section and adapted to be engaged by the outer edge of a hat.

4. A hat protector, comprising a body of waterproof, resilient material and composed of three distinct sections, one of which is disc-shaped, the other two resembling rings having smaller inner and larger outer diametrical dimensions, said sections being united with each other, resilient reinforcements provided at the joining edges of said sections and a heavy resilient reinforcement arranged at the outer edge of the largest section and serving for engaging the outer edge of the brim of a hat, said sections, when not in use, adapted to automatically collapse to a flat form in which one section rests upon and becomes adjacent to the other.

Signed at New York, in the county of New York and State of New York, this 17th day of September, A. D. 1926.

SALVATORE ANDRIOLA.
